(57) **CLAIM**

The ornamental design for a kneel down knee pad, as shown and described.

DESCRIPTION

FIG. 1 is a perspective view showing the top and left side of a kneel down knee pad which forms my new design;
 FIG. 2 is a perspective view showing the front, bottom and right side thereof;
 FIG. 3 is a top plan view thereof;
 FIG. 4 is a front elevational view thereof;
 FIG. 5 is a bottom plan view thereof;
 FIG. 6 is a left side elevational view thereof;
 FIG. 7 is a right side elevational view thereof;
 FIG. 8 is a rear elevational view thereof; and,
 FIG. 9 is a cross-sectional view thereof taken along lines 9-9 of FIG. 1.
